VALVELESS SAND PUMP

Leland J. Towne, Oklahoma City, and Edgar B. De Loe, Sapulpa, Okla.

Application May 7, 1937, Serial No. 141,336.

4 Claims. (Cl. 166—19)

The invention relates to sand pumps used in cleaning out sand and other foreign matter from deep wells.

The greatest difficulties with pumps of this class at present are the sticking of the plunger, and the sticking of the check valves due to sand and other foreign matter settling on top of and around the plunger and valves.

To obviate these difficulties various manufacturers have adopted the expedient of making the plunger somewhat smaller in diameter than the interior diameter of the barrel, with the idea that the sand and other foreign matter settling out of the liquid would pass downward in the barrel around the plunger. The actual results of this change in construction have been: extremely fast wear on the outer surface of the plunger, due to the abrasive action of the sand and other foreign matter in the liquid, causing frequent replacing of plungers and consequent loss of time; a great reduction in the vacuum pull of the plunger due to its very loose fit in the barrel; and the sticking of the plunger in the barrel due to the lodging of comparatively large hard bits of foreign matter between plunger and barrel. This last difficulty has proved costly due to the fact that the plunger usually sticks about midway of the barrel, and, as the pump is withdrawn from the liquid in the bottom of the well, the weight of the fluid and of the barrel causes the dislodging of the particles holding the plunger, and the loaded barrel drops, the impact of its head against the top of the plunger frequently breaking the sand line supporting the pump. Naturally the pump drops to the bottom of the well, and a fishing job is necessary, with consequent loss of valuable time. This construction has not greatly reduced the sticking of the check valves.

The chief objects of our invention, therefore, are to eliminate the above mentioned difficulties, which objects we accomplish by providing a pump having a valveless expandable plunger.

Other objects of the invention are: to provide a pump of this class, the plunger of which creates better suction than the plungers of pumps of present design; the plunger of which operates efficiently even though the pump barrel becomes accidentally dented; and which has fewer working parts than pumps of present design.

Other objects of the invention will be fully apparent from a consideration of the following detailed description of the invention when read in connection with the accompanying drawing

which form a part of this application. The drawing is to be considered illustrative only.

Referring to the drawing:

Figure 1 is a side sectional view of our sand pump assembled; 5

Figure 2 is a perspective view of one of the four shoes which form the plunger head, and shows by dotted lines the manner in which the shoes cooperatively fit together;

Figure 3 is a top sectional view taken along the 10 line 3—3 of Figure 1;

Figure 4 is a view similar to Figure 3 but shows the plunger head contracted; and

Figure 5 is a top sectional view taken along the line 5—5 of Figure 1. 15

Like characters of reference designate like parts in all figures.

The invention includes a barrel 10, a head 11, and a bottom 12. The bottom is provided with an upwardly opening pressure operated valve 13. 20 The barrel 10 is provided with a plurality of ports 14 and 15, which are so positioned that they lie below the plunger when it is at the upper end of its stroke. These ports thus serve as an outlet for fluid in the barrel above the plunger as 25 the plunger is drawn upward within the barrel, but as the plunger approaches the upper end of its stroke it closes these ports trapping liquid in the upper portion of the barrel above it. The only outlet for this liquid is through the opening 16 in the head around the sand line 17; thus the liquid above the plunger serves as a cushion to prevent the plunger operating rod from hitting the interior wall of the head with such force as to break the head, and the sand line. 35

The plunger includes a central plunger operating rod 18 threaded at its upper end as at 19 and connected to a usual rope socket 20, and having a flattened portion 21 to facilitate connection to the socket 20. Intermediate its ends the rod 40 is provided with an annular enlarged shoulder 22. A mandrel 23 is rotatably mounted on the lower portion of the rod below the shoulder 22, and is held in position thereon by a washer 24, a nut 25, and a cotter pin 26. The upper end of 45 the mandrel 23 is of larger diameter than its central portion and has a plurality of longitudinally extending slots 26 and 27, the office of which will be later described. Intermediate its ends the mandrel has a portion 28 of reduced 50 diameter formed by opposite converging frustoconical surfaces. The lower end 29 of the mandrel is square, as shown in Figure 5.

The plunger also includes an expandable head, designated as a whole by the numeral 30, and 55

composed of a plurality of interlocking arcuate shoes 31, 32, 33, and 34, the shape of which is more clearly shown in Figure 2. As illustrated, each shoe forms an equal portion of the complete circular plunger head, and interlocks with the adjacent shoes in a manner to permit radial movement with relation to the central rod 18 about which they are arranged. Each shoe has a slot 35 in its periphery, which slots serve as seats for the upper ends of reins 36, 37, 38, and 39, which are respectively secured to the shoes by means of counter sunk screws 40, 41, 42, and 43. Intermediate their ends, each of these reins is provided with an offset portion 44 which is so formed as to conform to the constricted portion 28 of the mandrel 23, when the upper and lower portions of the reins lie flat against the mandrel. The lower ends of the reins are slotted to receive the integral, spaced arms 51, 52, 53, and 54, of a rein yoke 45, which is centrally provided with a square through perforation of a size as to allow it to slidably fit the lower end 29 of the mandrel. The lower ends of the reins are held in position on the arms 51, 52, 53, and 54, respectively, by cotter pins 48, passing through the outer ends of the arms. This arrangement permits relative axial movement between the mandrel, and the yoke 45, the reins 36, 37, 38, and 39, and the head 30; and also permits each rein to pivot with its respective arm as an axis.

Figure 3 shows the head in its expanded position, its shoes completely sealing against the wall of the barrel 10. Figure 4 shows the head 30 partially contracted leaving an annular space 35 between the outer surface of the head and the inner surfaces of the barrel 10. With this arrangement it will be seen that the radial movement of each of the shoes away from the rod 18 accomplishes the expansion of the head as a whole, and that this radial movement of the shoes is accomplished by a movement of the mandrel 23 upward with relation to the reins 36, 37, 38, and 39. This movement causes the tapering shoulder 46 of the mandrel to contact the offset portions 40 of the reins, causing them to pivot, with their respective arms 51, 52, 53, and 54 as their axes, and forcing their upper ends outward toward the wall of the barrel 10. When the mandrel is again moved downward with relation to the yoke, 45, and with relation to the reins, the offset portions 40 of the reins seat in the constricted portion 28 of the mandrel, permitting the upper ends of the reins to move toward the rod 18, which of course permits the shoes 31, 32, 33, and 34, to move into their contracted position as shown by Figure 4, the upper ends of the reins seating in the like plurality of properly spaced slots 26 and 27 in the upper end of the mandrel 23.

We call attention to the fact that as the shoes 31, 32, 33, and 34, are moved axially away from the center rod 18, the center hole in the plunger head 30 is increased in diameter, and outwardly extending grooves are formed between the upper portions of the adjacent shoes and between the lower portions of the adjacent shoes. With the shoes in their expanded position, the grooves formed between the upper portions of the adjacent shoes have no outlet, and fluid in the upper portion of the barrel can not pass the plunger through these grooves. The grooves formed between the lower portions of these shoes, when the head is in its expanded form, serve as outlet ports for fluid above the plunger, due to the fact that the upper end of the mandrel 23 is of

less diameter than the interior diameter of the barrel 10. The upper end of the mandrel closes these lower grooves only a part of the distance outward from their inner ends, leaving their outer ends open at the bottom. This is an important feature of our invention as it prevents sand and other foreign matter from settling on top of the plunger, thus causing the piston to stick. As the sand settles out of the fluid trapped above the plunger, the circulation of the fluid through these settling sand with it to a point below the plunger head, where it passes out of the barrel when the pump is emptied.

Operation

15

In operation, the pump is lowered into the production tubing until it reaches the point in the well to be cleaned. During the downward travel of the pump, the plunger is at the upper end of its stroke, the valve 13 is free to open, and the fluid is free to pass upward through the barrel and out through the ports 14 and 15. When the bottom 12 seats on the sand or other foreign matter in the well, the plunger moves through the fluid to the bottom of the barrel due to its own weight, the fluid passing around the expandible head 30. An upward pull on the sand line 17 causes the mandrel 23 to move axially upward with relation to the reins, as previously described, thus expanding the plunger head 30. As the pull on the sand line is continued the plunger draws liquid into the barrel through the valve 13, and as the plunger approaches the upper end of the barrel its impact against the head is cushioned, as previously described. The entire pump is now drawn upward out of the well where it is emptied by unscrewing the set screw 47, and permitting the valve 13 to drop downward in the bottom 12, as shown by the dotted lines, and the operation is repeated.

While we have described and illustrated a specific embodiment of our invention, we are aware that numerous changes may be made therein and we do not wish to be limited except by the prior art and by the scope of the appended claims.

We claim:

1. A sand pump comprising: a barrel; a head for said barrel; a valved bottom for said barrel; a plunger within the barrel including an expandible head formed of a plurality of relatively movable interlocking shoes, a mandrel about which said shoes are positioned and with relation to which said shoes are radially movable, and a rein connected to each of said shoes and operable by said mandrel for moving said shoes radially; and means connected to said plunger and extending outside said barrel for moving said plunger with relation to said barrel, and for moving said mandrel with relation to said plunger head.

2. A sand pump including: a barrel; a head for said barrel; a bottom for said barrel; a plunger comprising a central plunger rod, a sectionally formed expandible head surrounding said rod intermediate its ends and movable axially with relation thereto, its individual sections being movable radially with relation thereto, a yoke mounted for limited axial movement on the lower end of said rod, and a plurality of reins each having its lower end pivotally connected to said yoke and its upper end rigidly secured to one section of said expandible head; and means connected to the upper end of said central rod and

55

extending outside the barrel for moving said plunger with relation to said barrel, and for moving said central rod with relation to said plunger head and said yoke, whereby said sectional head is expanded to seal against the wall of said barrel.

3. A pump plunger comprising: a mandrel mounted on a central plunger operating rod; a sectional expansible plunger head surrounding the 10 rod adjacent the mandrel; an axially slideable yoke on the mandrel; and means connecting the yoke to the individual sections of said head for moving the individual sections radially outward with relation to said mandrel and said rod when 15 the mandrel is moved axially with relation to said yoke.

4. A pump plunger comprising: a mandrel rotatably mounted on a plunger operating rod; a yoke mounted for limited axial movement only on the lower end of said rod; a plurality of radially movable interlocking shoes surrounding said rod adjacent the upper end of said mandrel and forming an expansible plunger head movable axially with relation to said rod; a like plurality of reins, each having one end attached to one of said shoes and the other end pivotally connected to said yoke; said reins adapted to expand said plunger head from its normally contracted form when said mandrel is moved upward with relation to said yoke and said head. 5 10
